David William Price, New York, N. Y.

Application October 17, 1935, Serial No. 59,088

Term of patent 3½ years

To all whom it may concern:

Be it known that I, David William Price, a citizen of the United States of America, residing in Manhattan, county of New York, and State of New York, have invented a new, original, and ornamental Design for a Dress, of which the following is a specification, reference being had to the accompanying drawing, forming part thereof, wherein,

Figure 1 is a front view of a dress showing my new design.

The characteristic feature of the design resides in the series of inturned horizontal tucks beginning immediately below the front part of the neck opening of the dress and descending and progressively increasing in length to the waistline.

I claim:

The ornamental design for a dress, substantially as shown, and described.
